UNITED STATES PATENT OFFICE.

SIMON MORRISON, OF NEW YORK, N. Y.

VANITY CASE.

Application filed May 20, 1926, Serial No. 110,355. Renewed March 8, 1928.

This invention relates to vanity cases and has for its particular object the provision of an improved loose powder unit having convenient means for making the powder available. The powder unit includes a hinged cover carrying a pivoted closure member, the latter being provided with propeller vanes which operate to push some of the contained powder from the unit as the closure member is moved to open position.

While I have disclosed a preferred embodiment of the invention for purposes of illustration, it will be understood that various changes and modifications in the structure could be made without departure from the true spirit and scope of the invention as hereinafter defined and claimed.

In the drawings;

Fig. 1 is a plan view of a vanity case embodying the invention;

Fig. 2 is a section on line 2—2 of Fig. 1;

Fig. 3 is a plan view of the powder unit with the hinged cover opened;

Fig. 4 is a section on line 4—4 of Fig. 1, with parts omitted.

Referring to the drawings more particularly, the vanity case 10 has a convex bottom wall 11 and carries a convex hinged cover 12. The loose powder unit 13 fits within the outer case 10 and conforms to the contour of said outer case. The unit 13 comprises a receptacle portion 14 and a cover 15 hinged thereto at 16. The cover 15 has a close frictional fit within the receptacle portion and carries a projecting lug 17 by which the cover may be lifted for refilling the powder unit.

Two sector shaped openings 18 and 19 are cut into the cover 15, leaving supporting arms 20 and 21 extending to the control hub 22. A disc closure member 23 pivotally secured to the hub 22 by a rivet 24 or other suitable fastening means, is adapted to cover the openings 18 and 19. Two triangular propeller vanes 25 and 26 are struck downwardly from the disc closure 23 and are diametrically located so that the resulting openings in the disc are normally covered by the supporting arms 20 and 21. An operating knob 27 is fastened to disc 23 in a position to contact with arm 21 when the openings in the disc lie beneath arms 20 and 21 to thereby act as a stop for the closed position of disc 23.

Two stop vanes 28 and 29 are struck upwardly from the bottom of the receptacle

portion 14, and are so located that one of the stop vanes lies just behind and sloping toward each of the propeller vanes.

When the vanity case is in the condition shown in Fig. 1 the powder unit is closed. Upon moving knob 27 in a clockwise direction the openings in the closure disc are moved away from the arms 20 and 21 and at the same time the powder from the receptacle is forced up the inclined propeller vanes 25 and 26 and deposited on the top of the closure disc where it is conveniently available for use. It will be seen that as disc 23 is rotated the propeller vane 25 will tend to press the powder toward the stop vane 29, and since the latter offers resistance to the movement of the powder the latter will be forced through the opening in front of vane 25. Similarly the stop vane 28 cooperates with propeller vane 26 to force powder from the receptacle. The arms 20 and 21 as well as closure disc 23 are dished as shown in Figs. 1 and 2 to provide a better surface for handling the powder.

I claim:

1. In a vanity case, a powder receptacle having a pivoted closure, an opening in the closure, and cooperating means carried by the receptacle and the closure for forcing powder from the opening.

2. In a vanity case, a powder receptacle having a closure, a propeller vane on said closure, an opening in said closure, and a stop on said receptacle cooperating with the propeller vane to force powder from the opening.

3. In a vanity case, a powder receptacle having a pivoted closure, a propeller vane on said closure, an opening in said closure, and a stop on said receptacle cooperating with the propeller vane to force powder from the opening.

4. In a vanity case, a powder receptacle having a pivoted closure disc, a propeller vane struck from said closure disc, an opening in said closure disc, and a stop vane struck from the receptacle and cooperating with the propeller vane to force powder from the opening.

5. In a vanity case, a powder receptacle having a pivoted closure disc, the receptacle having an arm for supporting the disc, a propeller vane struck from the disc and leaving an opening in the disc, said opening being normally covered by said arm.

6. In a vanity case, a powder receptacle

having a pivoted closure disc, the receptacle having an arm for supporting the disc, a propeller vane struck from the disc and leaving an opening in the disc, said opening being normally covered by said arm, and a stop on the receptacle and cooperating with the propeller vane to force powder from the opening.

7. In a vanity case, a powder receptacle having a pivoted closure disc, the receptacle having an arm for supporting the disc, a propeller vane struck from the disc and leaving an opening in the disc, said opening being normally covered by said arm, a stop on the receptacle and cooperating with the propeller vane to force powder from the opening, and a knob secured to the disc and forming a combined stop and operating means.

8. In a vanity case, a separate powder re-

ceptacle having a hinged lid, a closure disc pivoted to the lid, an opening in the lid, an opening in the disc, and means to force powder from the receptacle upon movement of the closure disc to bring the disc opening into communication with the lid opening. 25

9. In a vanity case, a separate powder receptacle having a hinged lid, a closure disc pivoted to the lid, an opening in the lid, an opening in the disc, a propeller vane carried by the disc, and a stop vane carried by the receptacle, said vanes cooperating to force powder from the receptacle upon movement of the closure disc to bring the disc opening into communication with the lid opening. 30

In testimony whereof I affix my signature.

SIMON MORRISON.
